Le Febure Corporation, Cedar Rapids, Iowa, a
corporation of Iowa

Application April 14, 1943, Serial No. 482,957

3 Claims. (Cl. 129—16)

This invention relates to sheet holding means and has particular relation to a locking tray adapted for selectively locking card or sheet records in place or adjustably releasing them in such a manner that they may be readily inspected or moved and replaced for making records thereon.

In some forms of record keeping, it is the usual practice to employ loose cards or sheets so that the cards may be removed and replaced readily in making entries but such sheets are frequently of a confidential and valuable nature so that it is desirable that they be locked or compressed into a solid block when not in use. There are several desirable features in locking the cards or sheets. One is that they are not available for casual inspection while in the locked position. Furthermore, the cards, while in locked condition are less likely to be burned in a fire inasmuch as they furnish a solid block of paper, the edges of which might char but the inner portions of which will not burn, except under extreme conditions of heat.

With records of this kind, however, it is very desirable that when the records are opened for use, a space be provided in front of the records, and other space be provided such that the records or cards will fall back into a tilted position best suited for easy manipulation of the records.

It is accordingly among the objects of my invention to provide means for accomplishing the desirable objects above pointed out and to provide a tray in which the ledger sheets may be locked solidly in place as desired or released in such a manner as to provide a working space at the front of the cards, and such that the rear supporting plate will be withdrawn a sufficient amount to permit the records to tilt back for ready manipulation.

Another important object of my invention is to provide a locking ratchet structure to bring the back compressor plate up to any desired position.

Still another object of my invention is to provide, generally, a tray of the above character which may be readily adjusted to hold various numbers of record sheets.

Other and further features and objects of my invention will be more apparent to those skilled in the art upon a consideration of the accompanying drawings and following specification, wherein is disclosed a single exemplary embodiment of the invention, with the understanding, however, that such changes may be made therein as fall within the scope of the appended claims,

without departing from the spirit of the invention.

In said drawings:

Figure 1 is a view in perspective of a tray constructed according to one embodiment of my invention. The retaining rails of the tray have been removed to better show the mechanism of the tray.

Figure 2 is a view in perspective of the upper face of the tray with the compressor plates removed and showing the ratchet plate and the screw mechanism.

Figure 3 is a view in side elevation of the tray as it appears with the compressor plates in closed position, and

Figure 4 is a view in side elevation of the tray as it appears with the compressor plate drawn to the open position, such opening having been accomplished only by the use of the key and screw mechanism.

Referring now to the drawings:

A device constructed according to a preferred embodiment of my invention employs a base, such as a rectangular pressed steel base, indicated at 10, covered with corduroy cloth, as at 11. A notch 12 is provided extending longitudinally of this base, and the sheets and compressors, hereinafter described, may be enclosed within rails indicated generally at 13 in Figures 3 and 4.

The notch 12 at the edges thereof is provided with rails or guides 15 on which blocks or traveling nuts 14 and 16 are slidably engaged. These blocks may be moved front and rear by means of the screw 17 which is journaled in bearings 18 at the end of the base 10 and rotated by means of a key 19.

I have found, in practicing my invention, that it is desirable in releasing the sheets, hereinafter described, to move the front compressor forward 40 several times as fast as the back compressor moves rearwardly. I therefore utilize two different pitches of threads on the screw 17. The portion of the screw 17 toward the front of the tray is preferably provided with a three-threaded screw, as at 171, while the back portion of the screw, as indicated at 172, will be a single thread. Thus the front block 14 moves three times as fast as the back block 16. This permits the sheets shown in Figures 3 and 4 to fall back slightly 45 while a considerable space is provided in front of the main block of sheets, as illustrated in Figure 4. The front compressor plate 21 has the lower portion 211 thereof secured to the block 14, while the upper portion 212 is hingedly secured 50 to the lower portion by means of the hinge con-

nection, indicated at 213. In locking the compressor plates, it is only necessary to push the plates up into the vertical positions shown in Figure 3, whereupon the locking mechanism 22, already known to the art, will lock this plate in its vertical position or in any desired position of tilt.

The traveling nut or block 16 has a traveling ratchet channel 23 secured thereto, as by means of the screws 24, and this ratchet channel is of substantially U shape with the edges of the channels cut to provide notches or teeth, as at 25 and 26.

A U shaped frame 31 is provided for carrying the back compressor plate 32 and this U frame 31 is secured to a block 33 which constitutes a follower or slide block slidable in the channel 23. The U-shaped member 31 is likewise a mounting frame for the ratchet mechanism as well as the compressor plate.

The ratchet or locking mechanism includes a pair of uprights 34 and 36 to which oppositely disposed operating levers 37 and 38 are pivotally secured. The levers 37 and 38 project outwardly through slots 39 and 41 in the vertically extending portions of the mounting frame 31 so that these levers may be operated from outside of the back compressor plate 32. The levers preferably are joined at their inner ends, as by means of the somewhat loose pivotal connection 42, and these levers have locking means or dogs 43 and 44 fixedly secured thereto. The upper ends of the locking means 43 and 44 are preferably joined by a spring 46 which thus tends to hold the dogs 441 and 431 in the bottoms of the teeth 26 and 23, to thus lock the mounting frame and back compressor plate onto the ratchet channel 23. A tongue 47 at the lower end of the compressor plate 32 projects between the locking means 43 and 44 when the compressor plate 32 is in a vertical position, but when the compressor plate 32 is tilted back to the inclined position shown in Figure 4, the tongue is withdrawn from between the locking means 43 and 44; so that the locking means are held in locked position when the compressor plate is in vertical position and are releasable when the compressor plate 32 is in inclined position. Thus the mounting frame and back compressor plate may be moved forward and back in the ratchet channel, as desired, by pushing down on the outer ends of the levers 37 and 38 and moving the plate to any desired position. Upon release of the levers 37 and 38, the dogs 441 and 431 of the locking means 44 and 43 again engage the teeth 26 and 25 and prevent rearward movement of the compressor plate.

It is apparent, upon inspection of the drawings, that when the compressor plates are in the locked position shown in Figure 3, the locking means 22 will prevent tilting of the front compressor plate 21 and the tongue 47, by reason of its position between the locking means 43 and 44, will prevent unlocking of the back compressor plate. Thus any records locked in the plates, as shown in Figure 3, cannot be readily removed except by unscrewing the threaded member 17.

When the screw 17 is rotated to release the sheets, the back mounting frame and compressor will move back one-third the distance of the movement of the front compressor plate, permitting the back compressor plate to tilt backward sufficiently for the cards or records in front of the plate to lean back against the back com-

pressor plate and permitting also adjustment of the back compressor plate in the ratchet channel as desired. Inasmuch as the front compressor plate moves at three times the speed of movement of the back compressor plate, a considerable space is provided in front of the records so that a working space is readily and quickly provided.

It is apparent that the release and movement of the back compressor plate and movement of this compressor plate in relation to the ratchet channel is interdependent and that movement of the compressor plate with relation to the channel cannot be accomplished except when the compressor plate is in the tilted position.

If desired, the tongue 47 may be eliminated and the notches at 51, which engage the lower edges of the outer ends of the levers 37 and 38 when the plate 32 is in a vertical position (Figure 1), relied upon to prevent downward movement of levers 37 and 38. When the papers in the tray are under compression, as in the locked position, the back compressor cannot be moved from the vertical. The notch at 51 will prevent downward movement of the levers and unlocking of the latch mechanism. It is to be noted that the notch at 51 is inclined or sloping and thus downward pressure on the levers 37 and 38 will cause the compressor 32 to tilt back from the vertical when the tray is unlocked and either of the levers or both of them pushed down.

Although I have described specific embodiments of my invention, it is apparent that modifications thereof may be made by those skilled in the art. Such modifications may be made so long as they do not depart from the spirit and scope of my invention as set forth in the appended claims.

I claim as my invention:

40. In a device of the class described, including a base and a front compressor plate, a screw for moving the front compressor plate, a ratchet channel adapted to be moved by the screw and having ratchet teeth, a mounting frame slidable in the ratchet channel for mounting a back compressor plate for tilting movement, a back compressor plate tiltable with respect to the mounting frame and having a ratchet for selectively engaging any of the teeth of the ratchet channel, and means operative by tilting of the back compressor plate for locking the ratchet into engagement with the ratchet teeth.
45. In a device of the class described, a base, a frame slidable on the base, a compressor plate pivotally attached to the frame, and locking means actuated by positioning of the compressor plate in a vertical position to lock the frame with reference to the base, and said locking means being so constructed that moving of the compressor plate back to a tilted position unlocks the locking means.
50. In a device of the class described, means for locking a plurality of sheets in a solid block-like form comprising a base and compressor plates, one of said compressor plates being pivotally mounted on a frame slidable with respect to the base, locking means for locking the frame with reference to the base comprising movable lever means, and means associated with the compressor plates for preventing movement of the lever means when the compressor plate is in vertical position.
55. In a device of the class described, means for locking a plurality of sheets in a solid block-like form comprising a base and compressor plates, one of said compressor plates being pivotally mounted on a frame slidable with respect to the base, locking means for locking the frame with reference to the base comprising movable lever means, and means associated with the compressor plates for preventing movement of the lever means when the compressor plate is in vertical position.
60. In a device of the class described, means for locking a plurality of sheets in a solid block-like form comprising a base and compressor plates, one of said compressor plates being pivotally mounted on a frame slidable with respect to the base, locking means for locking the frame with reference to the base comprising movable lever means, and means associated with the compressor plates for preventing movement of the lever means when the compressor plate is in vertical position.
65. In a device of the class described, means for locking a plurality of sheets in a solid block-like form comprising a base and compressor plates, one of said compressor plates being pivotally mounted on a frame slidable with respect to the base, locking means for locking the frame with reference to the base comprising movable lever means, and means associated with the compressor plates for preventing movement of the lever means when the compressor plate is in vertical position.
70. In a device of the class described, means for locking a plurality of sheets in a solid block-like form comprising a base and compressor plates, one of said compressor plates being pivotally mounted on a frame slidable with respect to the base, locking means for locking the frame with reference to the base comprising movable lever means, and means associated with the compressor plates for preventing movement of the lever means when the compressor plate is in vertical position.
